COMBINED RATTLE AND BABY POWDER CAN

Francis E. Blod, Tuckahoe, N. Y.

Application April 8, 1949, Serial No. 86,181

6 Claims. (Cl. 46—175)

1

This invention relates to amusement devices for infants and relates more particularly to a novel noise-making device or rattle which is associated with the upper wall of a dispensing container for baby powder or the like.

The amusement device of the present invention comprises the combination with a dispensing can for baby powder of a supplemental upper wall forming a closed chamber astride the powder chamber which contains solid particles such as lead shot which produce a characteristic rattle sound as the powder can is shaken for the purpose of applying the powder to the skin.

An important object of the invention is to provide a device of this character which can be applied to a conventional talcum powder can with shaker top without requiring any alteration whatsoever in the design or construction of the can.

Another object of the invention is to provide an amusement device of the character described which can be readily applied to the powder can after the same has been filled with powder and is otherwise ready for packaging.

Yet another object of the invention is the provision of a child's rattle or the like formed in combination with a baby powder can which in no way alters the effective dimensions of the conventional can so that when the rattle assembly has been applied to the filled can, the latter may be packaged in the same size of cardboard box that is presently used for the same powder container without the improvement of the present invention.

Still another object of the invention is to provide a novel powder can attachment forming a rattle which utilizes as one of its walls the upper wall of the standard sheet metal dispensing container and which, when applied to the can, cannot thereafter be removed therefrom, thus eliminating the possibility of the chamber containing the lead shot or other noise-making particles from being opened by the child.

A still further object of the invention is to provide a device of the character described which at a relatively small cost may convert a common talcum powder can into an article which has usefulness even after the powder has been used up.

In the drawing:

Fig. 1 is a plan view of an embodiment of the present invention.

Fig. 2 is a broken side elevation thereof.

Fig. 3 is an enlarged broken section taken on line 3—3 of Fig. 1.

Fig. 4 is an enlarged broken section taken on line 4—4 of Fig. 1.

Fig. 5 is a section similar to Fig. 3 but shows a modification in the construction.

A conventional dispensing can for baby powder or the like is shown in Figs. 1 and 2 and includes

2

10 a body section 10 and a cover section 11. The body section is illustrated as being generally square in horizontal section but it may be round, oval-shaped or otherwise without affecting the teachings of the present invention. After the can has been filled with powder the cover section or top 11 is applied thereto in the usual fashion.

15 The cover section includes a top wall 12, a continuous downwardly extending flange 13, an outwardly extending flange 14 and a second downwardly extending flange 15 which is received on the upper rim of the can in force-fit relation. It further includes a dispensing top including an upwardly extending central section 16 having openings 17 therein and an annular flange 18 around the upper edge. A rotatable cap or closure 21 is rotatably carried by this section, the edges of which are downwardly turned to form a continuous flange 22 which engages the lower edge of flange 18 to prevent removal of the cap. Openings 23 in the cap register with openings 17. All the foregoing is conventional.

20 The improvement constituting the present invention comprises a housing which may be formed of sheet plastic, suitably molded to shape, sheet metal, or other material. It includes a top wall 24 and a continuous, downwardly extending flange 25 which is received around the exterior of flange 13. It may also have an outwardly extending flange 26 which is seated on flange 14.

25 The central section of the upper wall is defined by a recessed portion comprising a downwardly extending annular wall 30 and an upwardly extending annular wall 31 which terminates in a horizontal section 32 whose inner edge defines a circular opening. This circular opening is of substantially the same diameter as the external 30 diameter of the side wall 33 of raised section 16 of the top section of the container.

35 A plurality of spaced, radially disposed slots 34 extend inwardly from the edge of the circular opening through the annular wall section 31 and at least a part of annular wall section 32. If the housing is formed from sheet metal these slots may have vertical walls although if it is formed of molded plastic they are preferably of dove-tail 40 contour and wider at their lower ends as shown at 35 in Fig. 4 since it is more expeditious to form the molding die in this manner.

45 To mount the housing on the can the housing may first be inverted and the small shot 36 then placed within the housing after which the central dispensing portion of the can is aligned with the central opening. The rotatable closure 21 is then forced through the opening, causing the jaw sections 31 to retract during this passage. As soon as the jaw sections clear the flange 22 50 they snap inwards into engagement with cylind-

drical wall 33 and the housing is locked in place. During this passage the flange 25 of the housing moves downwardly over flange 13.

In the modified arrangement of Fig. 5 the top 38 of the container has a slightly longer neck 39 and the rotatable cap 40 is also somewhat longer than that shown in Fig. 3. The lower edge 41 of the housing 42 in this instance rests upon the upper wall 43 of the top and the upper edge 44 of the housing thus occupies a lower position 10 relative to the rotatable cap. Thus, the cap is more readily rotated since there is more finger room as will be evident from a comparison of Fig. 5 with Fig. 2.

In this instance the inner edge 45 of the opening in the housing is received under the shoulder formed by the lower edge 46 of the rotatable cap or it may be so proportioned as to be received in an annular recess 47 in the cap. In either instance, the housing is moved easily over the cap during which movement the jaw sections 31 retract outwardly until the housing is in place at which time the jaw sections move inwardly.

While two forms or embodiments of the invention have been shown and described herein for illustrative purposes, and the construction and arrangement incidental to specific applications thereof have been disclosed and discussed in detail, it is to be understood that the invention is limited neither to the mere details or relative arrangement of parts, nor to its specific embodiments shown herein, but that extensive deviations from the illustrated forms or embodiments of the invention may be made without departing from the principles thereof.

What I claim is:

1. The combination with a container for powder or the like and provided with an upper wall having a raised, perforated dispensing top and a rotatable flanged closure therefor, of a noise making device comprising a housing having an opening which receives said raised top and including a top wall and a side wall extending downwardly to the upper wall of the container and forming therewith a closed chamber, jaw sections of resilient material formed around the edge of such opening which are arranged to retract by yielding as the housing is moved downwardly over the rotatable closure, the edges of said jaw section being arranged to underlie and engage the flange on the closure to retain the housing in place, and a movable noise-making member within the closed chamber.

2. The combination with a container for powder or the like and provided with an upper wall having a raised, perforated dispensing top and a rotatable flanged closure therefor, of a noise-making device comprising a housing having a top wall and a flange extending downwardly from the periphery thereof which receives the upper edge of the container and which forms with such upper wall a closed chamber, such top wall having an opening of substantially the same diameter as the raised top of the container, the edge of the opening being received below the edge of said flanged closure, such top wall being provided with an annular recessed portion between such opening and the margins of such top wall, said recessed portion having spaced, radially disposed slots extending outwardly from the edges of the opening to provide jaw sections which are arranged to retract as the housing is moved downwardly over the rotatable closure, and a movable noise-making member within the closed chamber.

3. In a container for powder or the like and

provided with an upper wall having a central, raised, perforated dispensing top and a rotatable flanged closure therefor, the combination of a noise-making device comprising a housing having an opening through which the raised dispensing top extends and comprising a top wall and a flange extending downwardly from the periphery thereof to the upper wall of the container and forming therewith a closed chamber, a solid particle disposed within such chamber and adapted to produce sounds as the container is agitated, such top wall being provided with an annular recessed portion adjacent such upper wall, said recessed portion having spaced, radially disposed slots extending outwardly from the opening to provide jaw sections which are caused to retract as the housing is moved downwardly over the rotatable closure, the edges of said jaw sections defining said opening and being arranged to underlie the flange on the closure to retain the housing in place.

4. The combination with a container for powder or the like and provided with an upper wall having a raised, perforated dispensing top and a rotatable flanged closure therefor, of a noise-making device comprising a housing having a top wall and a flange extending downwardly from the periphery thereof which engages the upper wall of the container and which forms with such upper wall a closed chamber, such top wall having an opening of substantially the same diameter as the raised top of the container and through which said raised top extends, and the top wall being provided with an annular recessed portion between such opening and the margins of such top wall, said recessed portion having spaced, radially disposed slots extending outwardly from the opening to provide plural jaw sections which retract as the housing is moved downwardly over the rotatable closure, the edges of said jaw sections defining said opening and being arranged to underlie the flange on the closure to retain the housing in place, and a movable noise-making member within the closed chamber.

5. The combination with a container for powder or the like and provided with an upper wall having a raised, perforated dispensing top and provided with an annular recess which forms a shoulder, of a noise-making device comprising a housing having a top wall and a flange extending downwardly from the periphery thereof which engages the upper wall of the container and which forms with such upper wall a closed chamber, such top wall having an opening of substantially the same diameter as the raised top of the container and through which said raised top extends, the top wall being provided with an annular recessed portion between such opening and the margins of such top wall, said recessed portion having spaced, radially disposed slots extending outwardly from the opening to provide plural jaw sections which retract as the housing is moved downwardly over the rotatable closure, the edges of said jaw sections being arranged to underlie the shoulder associated with the top, and a movable noise-making member in the closed chamber.

6. The combination with a powder container provided with an upper wall having a raised, perforated dispensing top, of a noise-making device comprising a housing having a top wall with a central opening for receiving the raised top and having a flange which extends downwardly from the periphery of the top wall to the container, to form therewith a closed chamber, a

movable noise-making member within the closed chamber, and a rotatable closure mounted on the perforated dispensing top and having a part overlying said housing around the central opening therein to hold the housing down against the container.
